UNITED STATES PATENT OFFICE.

ROSS L. TULLIS, OF NEW HAVEN, CONNECTICUT.

DESIGN FOR A BIRD CAGE.

Application filed April 7, 1927. Serial No. 21,496. Term of patent 14 years.

To all whom it may concern:

Be it known that I, Ross L. TULLIS, a citizen of the United States, residing in New Haven, in the county of New Haven and State of Connecticut, have invented a new, original, and ornamental Design for a Bird Cage, of which the following is a specification when taken in connection with the ac-

companying drawings, in which the figure is a front elevational view of a bird cage embodying my new design.

I claim:

The ornamental design for a bird cage substantially as shown.

ROSS L. TULLIS.
